UNITED STATES PATENT OFFICE.

ROY GREEN, OF BODCAW, ARKANSAS.

SAWING-MACHINE.

1,283,738.

Specification of Letters Patent. Patented Nov. 5, 1918.

Application filed February 9, 1917. Serial No. 147,685.

To all whom it may concern:

Be it known that I, ROY GREEN, a citizen of the United States, residing at Bodcaw, in the county of Nevada and State of Arkansas, 5 have invented certain new and useful Improvements in Sawing-Machines, of which the following is a specification.

This invention has relation to wood sawing machinery, and the nature and objects 10 thereof will be readily apparent to those skilled in the art to which it appertains in the light of the following explanation of the accompanying drawings illustrating what I now believe to be the preferred embodiment, 15 or mechanical expression of my invention, from among other forms and arrangements within the spirit thereof or the scope of the appended claims.

However, an object of the invention is to 20 embody in a log sawing machine of this type including a log supporting carriage movable by a piston reciprocable in a steam cylinder, of means readily operable by the sawyer or others to cut off the steam supply to 25 the cylinders in an emergency to immediately stop the operation of the sawing machinery.

Another object of the invention is to provide an apparatus of this character adapted 30 to positively cut off the steam supply to the cylinder regardless of position of the sawyer's valves which control admission of steam to the cylinder.

A still further object of the invention, is 35 to provide means for locking the mechanism of my invention when the same has been actuated in an emergency, thereby preventing further operation of the wood sawing machinery, until various adjustments in the 40 emergency machinery have been made.

In addition to the foregoing my invention comprehends improvements in the details of construction and arrangement of parts to be hereinafter more fully described and particularly set forth in the appended claims.

In the accompanying drawings in which similar and corresponding parts are designated by the same characters of reference throughout the several views in which they 50 appear:

Figure 1, is a view in side elevation with parts in section of a log sawing machine illustrating the embodiment therein of my invention.

Fig. 2, is a vertical transverse section 55 taken on the line 2—2 of the preceding figure.

Fig. 3, is a horizontal section taken on the line 3—3 of Fig. 1.

Fig. 4, is a detail vertical section taken on 60 the line 4—4 of Fig. 1, and

Fig. 5, is a detail view.

In Fig. 1 of the drawings I have illustrated portions of a log sawing machine for the purpose of illustrating the manner in 65 which my invention co-operates therewith, and all unnecessary details of the machine have been omitted. With reference to Fig. 1, 10 indicates a carriage adapted to support a log which is indicated at 11. The carriage after the usual manner is supported in a horizontal position for reciprocation upon rails 12, and the carriage, at its forward end is provided with a depending lug 13 to which the forward end of a piston rod 14 is secured. Located beneath the carriage and disposed in parallelism therewith is a relatively long steam cylinder within which the piston rod 14 extends. The piston rod is provided within the cylinder with a piston 16, and the cylinder is provided at opposite 70 ends with inlet ports 17 utilizable also as exhaust ports.

Sawyer's valves 18 are located beneath the cylinder 15 adjacent each end thereof, 85 and each cylinder is provided with a port 19 placed in communication with the inlet port 17 of the cylinder through the medium of short sections of pipe 20. Each sawyer's valve is furthermore provided at its side 90 opposite the port 19 with inlets and exhaust ports 21 and 22 respectively. Each sawyer's valve is of a hollow construction to permit the reciprocation therein of a piston valve 23, which piston valves are adapted for 95 movement in unison through the medium of a rod 24. The piston 23 at the forward end of the cylinder is likewise provided with a rod 24 which extends to a point adjacent the saw 26 of the sawing machinery and is 100 pivotally connected to a bell crank 27, to which bell crank the lower end of the sawyer's lever 28 is pivotally connected. The sawyer's lever is fulcrumed at a point substantially intermediate its end as at 29

105 in suitable bearings 30 after the usual manner, and whereby upon oscillating the said lever the piston valves 23 may be recipro-

cated in one direction or the other thereby alternately establishing communication between the supply ports 21 of the valves and the inlet ports 19 thereof, or between the 5 inlet ports 19 and the exhaust ports 22 of said valves. In this manner, the steam may be admitted into either end of the steam cylinder, so as to move the piston 16 from one end to the opposite end and back again 10 to thereby move the carriage and thereby bring the log into engagement with the saw, and to move the log away from the saw previous to adjusting the same laterally for sawing another plank. The foregoing description 15 is that of a standard type of log sawing machine, and hence I do not claim any of the mechanism embodied therein, but claim as my invention the mechanism to be hereinafter described.

20 Each supply port 21 of the sawyer's valve 18 is in communication with a supply pipe 31 and in each of said pipes there is interposed an emergency valve indicated generally at 32. Each of said valves is substantially cylindrical in configuration preferably disposed in a horizontal frame and in alignment, and each formed with a longitudinal central bore 33. A valve 34 is movable in each of said bores and each valve is 25 formed upon its forward end with a conical valve portion 35. Each valve is formed with a pair of opposed ports 36 in communication with the supply pipes 31 and a valve seat of conical formation indicated at 37 30 is formed at the forward end of each of said valve casings. It will be obvious from the foregoing that when the valves 34 are disposed with their conical portions 35 in engagement with the seats 37 the body portion 35 of the valve will be interposed between the ports 36 of the valve thereby cutting off any communication between the opposite sections of the pipe 31 and thereby preventing any admission of steam to the 40 sawyer's valve. Normally however, the valves 34 are disposed out of engagement with their seats and therefore the continuity of the pipe 31 is uninterrupted whereby steam may be admitted to the sawyer's 45 valves at all times.

50 Each valve casing 32 is provided upon its under side with a transversely and vertically extending opening which extends through the wall of the valve and intersects the central bore 33, for the purpose of guiding for movement therein a pin 38 to the lower end of which is pivotally connected a lever 39 fulcrumed at an intermediate point as indicated at 40 upon a bracket 41 mounted 55 upon the supply pipe 31. The opposite end of the lever 39 is provided with a weight 42 whereby to urge the pin 38 in an upward direction. The upper end of the pin 38 normally bears against the body portion of 60 the valve 34 except when said valve is moved

to closed position whereupon the pin is urged upward and the rear end of the valve is moved forward and unlaps the opening through which the pin 38 projects. In this event the pin 38 is moved upward and bears 70 against the rear end of the valve thereby preventing any backward movement of said valve and retains the same locked to its seat.

The rearward emergency cylinder 32 is formed upon its forward end with a pair 75 of horizontal extending more or less curved spaced arms 43 which are connected at their extremities by a horizontal shaft 45 and at a point intermediate their length by a shaft 46. Said shaft 45 supports a pair of spaced 80 levers 47 adapted normally to hang at their lower ends in front of a trip plate 48 which is adjustably secured to a rod 49, which connects the valves 34 for reciprocation in unison, a rod 50 being connected to the forward end of the valve in the forward casing 32. These rods in each instance extend through suitable packing glands in the valve casings to prevent the escape of steam therefrom. Mounted upon the above mentioned 90 shaft 46 which connects the arms 43, are a pair of bell cranks 51 having one of their arms extending upwardly and connected to the upper ends of the above mentioned levers 47 through the medium of links 52, while 95 the oppositely extending arms of the bell cranks 51 are provided with depending terminals 53 for the purpose of engaging in front of a retaining plate 54 which is secured to the rod 49 at a point just behind 100 the trip plate 48. Extending forwardly from the rear emergency valve are a pair of rods 55 disposed parallel to the rod 49, at opposite sides thereof and in horizontal alignment therewith. Said rods also extend 105 through openings in the retaining plate 54 and springs 56 are encircled about each of said rods and interposed between said retaining plate 54 and the valve casing 32 whereby to urge the plate and consequently 110 the rod 49 to which it is secured in a forward direction. It is to be noted however, that the springs are held under tension by the engagement of the terminals 53 of the bell cranks 51 with the said retaining plate. 115

Located at opposite sides of the sawyer's lever 28 and in the path of movement thereof are a pair of arms 57 fixedly mounted, and extended in upwardly diverging relation as indicated in Fig. 2. Each arm 57 is provided upon its outer face with ears 58 adapted to form fulcrum points for vertically extending levers 59 having at their upper ends set screws 60 whose threaded shanks extend through openings in the arms 57 120 whereby the sawyer's lever may engage during oscillation one or the other of the set screws to rock the levers 59 upon which they are mounted. A bar 61 is extended transversely of the sawing machinery and in a 125 130

horizontal position with one end disposed beneath the sawyer's lever in close proximity thereto and the other end disposed adjacent the outer extremity of the emergency valve 5 rod 50. The lower ends of the above mentioned levers 59 are each pivotally connected to depending links 62 which in turn are each connected to a separate bell crank 63, said links being connected to the horizontally disposed 10 arms of said bell cranks, the vertical arms of said bell cranks being in turn pivotally connected to the transverse bar 61. The opposite end of the bar 61 is pivotally connected to a longitudinally extending horizontal arm 64 rigidly connected at its opposite end to a vertical shaft 65 mounted for rotation in suitable bearings, the lower end of said shaft having rigidly secured thereto one end of a transversely extending 15 horizontal arm 66, the opposite end of which is pivotally connected to the emergency valve rod 50. The valve rod 50 is extended beyond this point of connection, and the extremity thereof is connected to the vertical arm of a bell crank 67, the horizontal arm of which supports an adjustable weight 68. Owing to this arrangement it will be obvious that a strain is constantly placed upon the emergency valve rod to insure the movement of 20 the valves toward a closed position. The end of the bar 61 remote from the point of connection thereof to the arm 64 is provided with a weighted bell crank 69 similar to the bell crank 67 whereby movement longitudinally of said bar in one direction is urged. A bell crank 70 may also be provided having a vertical arm pivotally connected to the bar 61, and a horizontal arm pivotally connected to the lower end of a vertical rod 70^a 25 having at its upper end a foot pedal.

The operation of the emergency valves is only designed to take place when an accident occurs to the wood sawing machinery whereby stoppage thereof is necessitated, and in 30 this event the actuation of the valves may be brought about in several ways. If the sawyer's lever 28 is moved in either direction to an extreme position, or until one or the other of the set screws 60 are engaged, the lever 59 supporting the engaged set screw will be 35 rocked whereby the corresponding bell crank 63 will be similarly rocked to move the bar 61 longitudinally and in a direction toward the sawyer's lever thereby rocking the vertical shaft 65 owing to the connection of its 40 arm 64 with the bar whereby the emergency valve rod 50 will be drawn forward. The rod 49 connecting the emergency valves will be moved in the same direction as the rod 45 50 and to the same extent thereby oscillating the levers 47 owing to the engagement thereof with the trip plates 48 which is mounted upon the rod 49. The bell cranks 51 will therefore be oscillated owing to the 55 connection thereof with the said levers 47

whereupon the downwardly extending terminals 53 of said bell cranks 51 will be disengaged from the retaining plate 54. When the retaining plate 54 is thus disengaged the rod 49 may be further moved forward thereby carrying the emergency valves 34 to their seats and permitting the pin 38 to be disposed behind said valves and thereby locking them in place. 70

In order that sufficient movement of the trip plate 48 may be permitted before the down-turned ends 53 of the bell cranks 51 are entirely disengaged from the retaining plate, the rod 49 may be provided with an elongated opening 71 in which the end of a set screw 72 projects, said set screw being threadedly engaged in a hub 73 formed on said retaining plate. The springs which encircle the rods 55 and which are designated 80 56 are of a sufficient tension to normally urge the retaining plate forward so as to dispose the set screw in the forward end of the elongated opening 71 of the rod 49. Thus, a sufficient forward motion of the rod 49 is permitted equal to the length of the slot 71 in 85 order to permit the retaining plate to become fully engaged. Thus it will be seen that owing to the provision of this improved mechanism, the valves 34 are held in an unseated position at all times and cannot be 90 moved toward a seated position except through actuation of the rods 49 and 50 in one direction. Furthermore, the valves can be locked against movement absolutely by releasing the set screw which binds the plate 48 95 to the rod 49 and moving said plate toward the left which will prevent disengagement of the levers 51 from their plates 54 even when the rod 49 is actuated. 100

It will be obvious by depressing any one 105 of the above mentioned foot petals 70^a the bar 61 will be moved to move the emergency valves to their seats in the manner described above. In this manner should an accident occur to the sawing machinery 110 while no one is stationed near the sawyer's lever, the machinery may be stopped at points remote from the lever. The wood sawing machinery is also rendered safe against operation by an irresponsible or inexperienced sawyer as should the sawyer's lever be moved too far in either direction a stoppage of the wood sawing machinery will 115 obviously occur.

While I have illustrated and described 120 my invention with some degree of particularity, I realize that in practice various alterations thereover may be made, and I therefore reserve the right and privilege of changing the form of the details of construction or otherwise altering the arrangement of the correlated parts without departing from the spirit of the invention or the scope of the appended claims. 125

Having thus described my invention what 130

I claim as new and desire to secure by Letters Patent, is:—

1. In a log sawing machine including a log carriage, a cylinder and piston for moving said carriage, sawyer's valves for controlling admission of steam to the cylinder, and a lever mechanism for operating said valves, the combination therewith of an emergency valve for each sawyer's valve to cut off the steam supply thereto, means engageable by the sawyer's valve when moved to an extreme position to close said emergency valves and foot pedals located at various points about the sawing machine for operating said valve operating means.
2. In a log sawing machine, including a log carriage, a cylinder and piston for moving said carriage, sawyer's valves for controlling admission to the steam cylinder, and a lever mechanism for operating said valves, the combination therewith of a valve for cutting off steam supply to said sawyer's valve and means operable by an extreme movement of the sawyer's lever for closing said cut off valve.
3. In a log sawing machine, including a log carriage, a cylinder and piston for moving said carriage, sawyer's valves for controlling admission of steam to the cylinder, and a sawyer's lever mechanism for operating the said valves, the combination therewith of an emergency valve for each sawyer's valve for cutting off the supply of steam thereto, a rod connecting the emergency valves for operation in unison, and means operable by an extreme movement of the sawyer's lever for closing the emergency valves.

Copies of this patent may be obtained for five cents each, by addressing the "Commissioner of Patents, Washington, D. C."

4. In a log sawing machine including a log carriage, cylinder and pistons for moving said carriage, sawyer's valves and lever mechanism for operating the valves, the combination therewith of an emergency valve for each of said sawyer's valves, a rod connecting the valves to insure movement thereof in unison, a rod for actuating the valve, locking means tending to prevent movement of the valves in one direction, and means operable instantly upon movement of the valves to release said locking means, said releasing means being shiftable to a position out of operative relation with the locking means to insure the locking of the valves against movement in one direction.
5. The combination with a log sawing machine, of an emergency valve for controlling the admission of steam thereto, a rod for actuating the valve, a collar carried by the rod, a locking pawl engaging the collar to prevent motion of the rod in one direction, a pawl operatively connected with the locking pawl to release the same, and a slideable collar on the rod engaging the operating pawl to release the locking pawl immediately upon movement of the rod, said sliding collar being movable to position out of engagement with the operating pawl whereby to insure locking of the rod against movement in one direction.

In testimony whereof I affix my signature in presence of two witnesses.

ROY GREEN.
